UNITED STATES PATENT OFFICE.

HERBERT E. WHITE, OF YOUNGSTOWN, OHIO, ASSIGNOR TO THE TRUCSON STEEL COMPANY, OF YOUNGSTOWN, OHIO, A CORPORATION OF OHIO.

BOTTOM-HUNG-SASH CONSTRUCTION.

Application filed February 10, 1921. Serial No. 443,951.

To all whom it may concern:

Be it known that I, HERBERT E. WHITE, citizen of the United States, residing at Youngstown, in the county of Mahoning and State of Ohio, have invented certain new and useful Improvement in Bottom-Hung-Sash Constructions, of which the following is a specification.

This invention relates to an improvement in ventilating sash construction for buildings, and has particular reference to a bottom hung sash unit having an automatic weathering joint between the top edge thereof and the framework of the building.

Accordingly a primary object of the invention is to provide in combination with the desirable feature of a bottom hung sash unit, a novel weathering member cooperating with the upper or swinging edge thereof in such a manner as to provide a weather-tight joint for the top of the sash unit while at the same time not interfering with the adjustment of the latter for ventilating purposes. In that connection, a further object of the invention is to provide in combination with the bottom hung sash unit, a weathering member which will be automatically shifted to an out of the way position without the aid of mechanical devices to permit the sash to swing freely outward, and likewise upon its return to a closed position, it may be automatically engaged with the weathering member to automatically form the joint.

It is to be noted that heretofore it has been impractical to effectually utilize a bottom hung sash construction because of the fact that a satisfactory weather-tight joint could not be formed between the upper edge of the sash and the framework of the building, but the present invention meets the requirements in that respect and makes it possible to use a sash of the bottom hung type with the minimum of operating devices, thereby not only simplifying the mechanism involved but at the same time reducing the cost of installation and adding materially to the reliability and usefulness of the device because of its simplicity of design and arrangement.

With the above and other objects in view, which will more readily appear as the nature of the invention is better understood, the same consists in the novel construction, combination and arrangement of parts here-

inafter more fully described, illustrated and claimed.

A preferred and practical embodiment of the invention is shown in the accompanying drawing, in which:

The figure is a vertical sectional view of a bottom hung sash unit showing the sash in its closed position in full lines and in its open position in dotted lines, the relative position of the canopy or weathering strip being also shown.

In large buildings such as foundries, glass works, forge shops and the like requiring extensive ventilation, a sash construction of the bottom hung type, such for example as that shown in my copending application filed February 10, 1921, Serial No. 443,950 is very desirable.

In the construction of the invention referred to in the above application, the important feature of providing an adequate weather-tight joint at the top edge of the sash is provided for by means of a hand or mechanically operated weathering element, but the present construction has in view a simplified form of construction wherein the weathering unit or canopy is operated automatically by the movement of the bottom hung sash, and by gravity.

Accordingly, as will be observed from the accompanying illustration, it is proposed to mount the bottom hung sash unit S upon the supporting hinge member 1 carried by one of the upright frame members of the building structure whereby it may be swung outwardly and inwardly through the operating connection O to permit its upper frame member 2 to move toward and from its former position to provide a variable discharge passage or ventilating outlet.

When the said bottom hung sash is in its normal closed position, its upper edge 2 is weather sealed by a novel weathering strip unit designated in its entirety as 3. This novel unit is pivotally suspended in a suitable position above the top edge of the sash whereby it may freely engage and disengage with the sash to provide an overlapping weather-tight joint, and although this unit may be embodied in various structural forms, a preferred and practical type thereof is shown in the accompanying drawing, wherein it will be observed that the same primarily consists of the continuous weathering strip or plate 4 provided at its upper

end with an outwardly turned hook flange 5 adapted to engage in the angle or groove of the continuous supporting member 6 thereby constituting a hinge for permitting 5 the weathering strip to rock or swing with the movement of the sash.

The lower edge portion of the weathering strip 4 is preferably bent inwardly as at 7 to provide a sealing edge adapted to engage with the outer flange of the channel member 2, and the inner face of said strip preferably carries a hood forming angle plate 8 having the attaching flange portion 9 and the depending abutment flange portion 10 for engaging with the opposite flange of the channel member 2 of the sash. The hood plate 8 with its depending abutment flange 10 cooperates with the sealing flange 7 of the weathering strip to provide 15 an effective hood or bonnet for receiving the entire upper edge of the sash when the latter is in its upright or closed position. The said channel member 2 of the sash has a relatively snug fit within the mouth of the hood, and yet has ample operating clearance to become disengaged therefrom upon the outward movement of the sash. The upper portion of the weathering strip 4 is preferably provided with a counterweight 20 receiving chair 12 for receiving a suitable weight which will have a tendency to rotate the entire weathering unit from the full line position shown to the dotted line position, so as to hold and maintain the strip in an outward position to receive the upper edge of the sash when the latter swings from an open to a closed position.

By reference to the manner of operation and functioning of the parts, it will be observed that when the sash and weathering unit are in the full line position shown in the illustration, the weather-tight connection between the sash and the canopy or weathering strip is complete. However, when it is desired to open the sash for ventilating purposes, the operating mechanism O comes into play to permit the upper edge of the sash to swing outwardly to the dotted line position, whereby the movement of the sash will carry the weathering unit to the dotted line position shown by reason of the channel member 2 engaging with the sealing flange 7 along the bottom edge of the weathering strip. Upon the return movement of the sash, the opposite flange of the channel 2 will strike against the abutment flange 10 of the hood to thereby rock the entire weathering unit back into its full line position, against the resistance of the counterweight within the chair 12. It will, therefore, be apparent that the operation of the weathering unit or canopy is entirely automatic.

Without further description, it is thought 65 that the features and advantages of the in-

vention will be readily apparent and it will of course be understood that changes in the form, proportion and minor details of construction may be resorted to without departing from the spirit of the invention or 70 scope of the appended claims.

I claim:

1. A sash construction for buildings including a sash unit having a hinge support at its bottom edge, and movable means connecting with and operated from the top edge of the sash for automatically forming a 75 weather-tight joint therewith.

2. A sash construction for buildings including a sash unit having a hinge support 80 operated from its bottom edge, and a shiftable weather-tight joint forming unit at the upper edge of the sash and adapted to automatically engage and disengage therewith.

3. A sash construction for buildings including a sash unit having a hinge support at its bottom edge, and means for automatically forming a weather-tight joint at the top edge thereof, said means comprising a pivotally supported canopy member adapted 85 to be shifted on its pivotal support by the movement of the upper edge of the sash.

4. A sash construction for buildings including a sash unit having a hinge support at its bottom edge, and means for automatically forming a weather-tight joint at the top edge of the sash, said means consisting of a continuous canopy member pivotally suspended above the upper edge of the sash and having a depending hood portion adapted 95 to engage with opposite sides of the top edge of the sash to be shifted thereby.

5. A sash construction for buildings including a sash unit having a hinge support at its bottom edge, and means for automatically forming a weather-tight joint at the top edge of the sash, said means comprising a pivotally suspended counter-balanced member formed at its lower edge to straddle the top edge of the sash whereby the movement of the latter will automatically shift said joint forming means to an open and closed position.

6. A sash construction for buildings including a sash unit having a hinge support 115 at its bottom edge, and means for automatically forming a weather-tight joint at the top edge of the sash, said means comprising a plate member having a hinge support at its upper edge while its lower edge may overlap with the top frame member of the sash, a member carried by the said plate member for providing a spaced channel at the bottom thereof for forming a housing for the top frame member of the sash, and means 120 for supporting a counter-balancing weight also carried by the said plate member.

7. A sash construction for buildings including a sash unit having a hinge support at its bottom edge, and a counter-balanced 130

canopy member for automatically forming a weather-tight joint with the top frame member of the sash.

8. A sash construction for buildings including a sash unit having a hinge support at its bottom edge, means for controlling the shifting of the sash unit on its hinge support, and weather-tight joint forming means

at the top edge of the sash unit controlled by the movement of the sash.

10

In testimony whereof I hereunto affix my signature in the presence of two witnesses.

HERBERT E. WHITE.
